United States Patent Office.

JAMES W. LYON, OF BROOKLYN, NEW YORK.

Letters Patent No. 77,059, dated April 21, 1868.

IMPROVEMENT IN LAMP-SHADE SUPPORTERS.

The Schedule referred to in these Letters Patent and making part of the same.

TO ALL WHOM IT MAY CONCERN:

Be it known that I, JAMES W. LYON, of the city of Brooklyn, in the county of Kings, and State of New York, have invented certain new and useful Improvements in Shade-Holders for Lamps; and I do hereby declare that the following is a full and correct description thereof, reference being had to the annexed drawing, and the letters of reference thereon.

The first part of my invention consists in constructing the clamping-ring centre of the shade-holder with a groove around the interior of the same, which groove corresponds with the bead formed upon the lower edge of the gallery of the flat-wick kerosene-burners, as universally made and sold in market.

The second part of my invention consists in adapting the clamping-ring centre to burners wherein the chimney is secured in its gallery by a thumb-screw, by making a part of the clamping-ring centre narrower than the rest, so as to pass under the screw, or otherwise removing a portion of the metal, so as to make room for the screw.

The third part of my invention consists in the adaptation of the clamping-ring centre to burners wherein the chimney is secured by a spring, commonly known as "Jones's Burners." This adaptation consists, in part, in having the clamping-ring centre so much shorter than the circumference of the burner that the spring may play freely between the ears of the clamping-ring centre, the clamping-screw being long enough to hold the ring in such position, and so placed as not to interfere with the action of the spring which holds the chimney.

The fourth part of my invention consists in combining, with radial arms which support the shade, a clamping-ring centre, which is adapted, as above described, for either a lamp-burner in which the chimney is secured by a thumb-screw, or one in which the chimney is secured by a spring, so that the shade-holder may be used, at pleasure, for either kind of burners without change, the provision for accommodating the thumb-screw of the one class of burners not interfering with the use of the shade-holders upon the burners which have the chimney-spring, and the provision for accommodating the spring not interfering with the use of the shade-holders upon burners which have the thumb-screw. I have shown, in the drawings, extensible radial arms attached to my improved clamping-ring centre; but it may be used with arms that are not extensible, the extensibility of the arms, whether by sliding or hinging, forming no part of the improvements hereinbefore described and set forth; but my invention further consists in combining a clamping-ring centre, such as is hereinbefore described, with extensible supporting-arms, which arms may be made extensible by hinging them to the clamping-ring centre, or a projection therefrom, or by slides, as heretofore practised in lamp-shade holders having different ring-centres.

It is well known that the greater proportion of lamps now used in this country have flat-wick kerosene-oil burners, and that these burners, although varying in many particulars, are made and sold in the market of certain determinate sizes with respect to the chimney-galleries, and, therefore, there is no difficulty in manufacturing my improved lamp-shade holder, and furnishing it separately, to be applied to kerosene-burners of a given size. All that is necessary is to make as many different sizes of shade-holders as there are different sizes of lamp-burners, should they vary greatly in size. It will be evident that a portion of my invention may be used without using the whole, as, for instance, the provision for the chimney thumb-screw may be disregarded, if the shade-holder is to be used only with burners that have chimney-springs, and the provision for the chimney-spring may be disregarded, and the ears of the clamping-ring centre brought nearly together, if the shade-holder is to be used only for burners which have chimney thumb-screws; but I have preferred to describe and show my invention in the form which enables it to be used with either class of burners, because that is the form of it which will be most useful and salable.

The drawings annexed illustrate my invention applied to lamp-burners—

Figure 1 being a plan view, and

Figure 2 a side elevation of the shade-holder applied to a burner which has a chimney thumb-screw, and

Figures 3 and 4 being, respectively, a plan view and side elevation of the same applied to a burner which has a chimney-spring.

Figure 5 is a view in perspective of the clamping-ring centre, and

Figure 6 is a section, showing the fitting of the groove in the clamping-ring centre to the bead on the lower edge of the gallery of the burner.

In figs. 1 and 2, the arms *a*, which support the shade, are shown extensible by sliding. In figs. 3 and 4, the supporting-arms *a* are extensible by hinges, *a'*. I have not shown a non-extensible arm in the drawings, as they are well known. The clamping-ring centre *b* is a strip of sheet metal, bent in a circular form, having projecting ears, *b'*, as shown clearly in the drawings. A screw being cut in one of the ears, the clamping-ring centre is drawn together by a clamping-screw, *c*. A groove, *d*, is formed, by stamping, or in any other convenient way, on the inside of the clamping-ring centre, at the lower part thereof, for the purpose of embracing the bead *e*, at the lower corner or edge of the chimney-gallery, so that the clamping-ring centre, when screwed fast to the burner, may be held firmly and rigidly thereto. At *f*, a portion of the metal of the clamping-ring centre is cut away, to make room for the chimney thumb-screw *g*. For the sake of symmetry, another similar portion, *h*, is also cut away. The groove *d*, when the clamp-ring centre is made of sheet metal, being a corrugation, stiffens the clamp-ring centre; and, for the purpose of strength and ornament, other corrugations, *i*, may be formed. The radial arms *a*, whether extensible or non-extensible, are attached to the clamping-ring centre at such distances apart as shall make them as near as may be equidistant from each other when the clamping-ring centre is applied to a burner of the size for which it is designed. It will be observed, by examining the drawings, that sufficient space is left between the ears of the clamping-ring centre to allow the chimney-spring *j* to play freely between the ears when thrown back to release the chimney, and the arms must, therefore, be attached to the clamping-ring centre with reference to leaving this space between the ears of the clamping-ring centre when it is applied to the burner, and, at the same time, with reference to being as near as may be equidistant from each other when clamped to the burner.

My improved shade-holder, by reason of its having a clamping-ring centre, and also by reason of the holding-groove *d*, and the provision of the chimney-screw, is also especially adapted to that class of kerosene-burners which have hinged chimney-holders, because, being clamped to the gallery, it permits the chimney-holder and chimney to be moved, by means of the hinge from over the wick-tube, without removing the shade-holder from the burner.

I claim as my invention and improvement in shade-holders for lamps—

1. Grooving the clamping-ring centre of the shade-holder on the inside, correspondingly with the bead on the lower corner of the chimney-gallery of a kerosene-lamp burner, substantially as described, whereby the clamping-ring centre is held securely in place, and enabled to gripe the strongest part of the gallery, substantially as set forth.
2. Adapting the clamping-ring centre of the shade-holder to burners which have chimney-screws, by removing a portion of the metal of the clamping-ring centre, which would otherwise interfere with the screw, substantially as described.
3. Adapting the clamping-ring-centre shade-holder to burners which have chimney-springs, by the relative arrangement of the radial arms with the clamping-ring centre, and its ears, and a clamping-screw of sufficient length, so that the spring can play freely between the ears when thrown down to release the chimney, substantially as set forth.
4. In combination with radial supporting-arms, a clamping-ring centre, constructed substantially as herein described, so that it may be applied either to a burner having a chimney thumb-screw, or to burners having chimney-springs, at pleasure, and without change.
5. In combination with a clamping-ring centre, extensible supporting-arms, whether sliding or hinged, substantially as described.

JAMES W. LYON.
